United States Patent

Des. 242,532

Patented Nov. 30, 1976

242,532

THERMOSTAT COVER

Harvey G. Skinner, Latrobe, Pa., assignor to Westmoreland Plastics Company, Division of Vulcan, Inc., Latrobe, Pa.

Filed Jan. 13, 1975, Ser. No. 540,401

Term of patent 14 years

Int. Cl. D10—99

U.S. Cl. D10—60

Fig. 1.

Fig. 2.

Fig. 3.

Fig. 4.

FIG. 1 is a top isometric view of a thermostat cover showing my design;

FIG. 2 is a left end elevational view thereof;

FIG. 3 is a top plan view thereof;

FIG. 4 is a front side elevational view thereof; the rear side being a mirror image thereto.

I claim:

The ornamental design for a thermostat cover, as shown.
